RAILWAY CAR CONSTRUCTION

Garth G. Gilpin, Riverside, Ill., assignor to Union Metal Products Company, Chicago, Ill., a corporation of Delaware

Application September 17, 1934, Serial No. 744,429

11 Claims. (Cl. 105—409)

The invention relates to railway cars and more particularly to side walls of open top railway cars. These side walls perform two functions. First, they are the load retaining means, and secondly, 5 they are girders carrying the major portion of the weight of the lading to the body bolsters from whence it is transferred to the trucks. In certain types of other railway cars my construction may also be used.

10 An object of the invention is to provide a very light and strong car wall which can be quickly and economically made, installed and repaired.

Such walls must be very light, as it is expensive to transport dead weight in a car and such walls 15 must be very strong as girders to carry the load referred to above and must be very strong as vertical beams to carry the horizontal thrust of the lading, which is very great on account of the impact thereof due to the movements of the car 20 when running. The parts of the wall must be capable of easy assemblage because replacements frequently are necessary on account of wearing out of the parts, corrosion and wrecks.

Another object of the invention is to provide 25 the side wall of an open top railway car with outwardly projecting panels between the vertical strut-ties to increase the cubical capacity of the car, and a further object is to provide some of the metallic wall sheets forming the retaining 30 wall of the car with an integral flange forming a strut-tie so as to increase the horizontal widths of the outwardly projecting panels longitudinally of the car whereby the cubical capacity of the car is further increased.

35 A further object of the invention is to provide an integral strut-tie of such depth as to project beyond the outwardly projecting panels in the wall sheets so as to protect the side walls from being scraped by objects along the right-of-way, protect 40 the lettering and other painting from being scraped or damaged and also to protect the side wall of the car when it is tipped upside down in an unloading machine.

Another object of the invention is to provide 45 means to prevent the strut-tie from deflecting laterally under stress, as such deflection would weaken the member both as a strut and as a tie, such means being preferably within the bounding 50 planes of the outwardly projecting panels, so that such panels may be extended to the maximum permissible width of the car whereby the greatest cubical capacity of the car is obtained.

Another object of the invention is to provide a 55 car wall so that the component parts thereof

may be secured together by bolting, riveting or welding.

Another object is to provide a car wall wherein the component parts can be made of pressed steel plates between reciprocating dies.

Another object is to provide a car wall to obtain the maximum cubical capacity of the car commensurate with the strength requirements.

Another object is to provide a car which will dump the entire lading when turned upside down 10 in an unloading machine.

Another object is to secure the ends of the strut beams (or one of them) to the frame members of the car so as to form restrained beams.

Another object is to form the integral flange 15 with a reflare so as to materially increase the strength thereof and also so this reflare may be secured to one or both of the frame members.

In the drawings:

Fig. 1 shows a partial side elevation of an open 20 top railway car provided with a side wall in accordance with my invention.

Fig. 2 is a section on line 2—2 of Fig. 1.

Fig. 3 is an enlarged section on line 3—3 of 25 Fig. 1.

Fig. 4 is a fragmentary perspective view of the exterior of the side wall of a car in accordance with my invention.

Fig. 5 is similar to Fig. 4 but shows an interior 30 view of the car.

Fig. 6 is a perspective view showing one means of preventing the strut beam from buckling under stress.

Figs. 7 and 8 show other means of preventing 35 the strut beam from buckling under stress.

Fig. 9 shows a modified construction of my invention wherein the adjacent wall plates are welded together.

In the form of my invention illustrated the 40 wall of the car comprises spaced apart upper (2) and lower (3) chords or other frame members and a plurality of wall plates 4 extending therebetween and forming the load retaining means of the wall as well as the web plate of the wall as a 45 girder.

Some of such wall plates are formed with an integral laterally and outwardly extending flange 6 at one vertical margin thereof to provide a strut beam between the frame members 2—3. 50 These flanges preferably overlap the frame members and are secured thereto so as to form a restrained beam to strengthen the strut beam. Each flange is preferably formed with a reflare 8 to increase its strength, which reflare 8 is 55

preferably secured to one or both frame members 2-3.

Each of the wall plates is formed with an outwardly projecting panel 10 so as to increase the cubical capacity of the car. The panel of the flanged plate 12 (Fig. 3) merges into the plate 14 adjacent the base of the flange 6 and the panel of the adjacent plate 16 merges into the plate 17, which plate 17 is secured to the flanged plate 12 adjacent the base of the flange 6. In other words, the panels merge into the body portion of the plates as close to each other as strength requirements permit so that the horizontal widths of the panels longitudinally of the car are increased (over the paneled side wall having separate strut beams) whereby the lading compartment of the car is further increased in cubical capacity. Figs. 3 and 6 show the flanged and the unflanged plate overlapped 20 and the rivets 19 secure the overlapped portions together, whereas Fig. 9 shows the flanged and unflanged plate designed for a welded connection wherein the sloping walls 20 and 22 of the adjacent panels 24-26 are even closer together than 25 in the riveted construction. Numeral 28 designates the flange and 30 the reflange.

The sloping parts 11-13 of the wall plates 12-16 respectively cooperate with the flange 6 to form a strong column and a strong beam (or 30 strut-beam) between the upper and lower frame members. The reflange 8 preferably projects towards the flanged wall plate so that the reflange 8, flange 6 and overlapping portion 18 (of the flanged wall plate) form a channel section, which is a very strong section.

In the preferred construction, the integral flange 6 or strut beam is greater in horizontal depth than the depth of the panels so that the flange 6 (or the reflange 8) projects beyond the 40 outer plane 40 of the panels, thus protecting the panels in the wall sheets. See Fig. 3.

A single beam member, such as the flange illustrated, deflects laterally under stress, thereby weakening the member as a beam and also as a 45 strut, therefore, I preferably provide means to prevent the strut beam from deflecting laterally under stress such as the triangular shaped indentation 42 which may be positioned at spaced intervals along the flange 6 preferably between 50 the rivets 19. These indentations, or stiffening means, extend into a part of the flange and a part of the body of the plate.

Figs. 6, 7 and 8 show other forms of stiffening means for the flange wherein Fig. 6 shows a strap 55 44 overlapping the reflange 8 and secured thereto, which strap is secured to both of the adjacent panels of the wall sheets. Fig. 7 shows a form wherein the short straps 46 and 48 are secured to the reflange 8 and the adjacent panels 60 but are positioned between the sloping webs 50-52 of the adjacent panels; i. e., within the bounding plane of the outwardly projecting panels. These straps 46-48 may be welded as shown 65 on the drawings or riveted. Fig. 8 shows an arrangement wherein a preferably flat plate 56 is welded to the flange 6 and the reflange 8 and also preferably to the body of the plate at 51.

Fig. 9 shows a modification wherein the flanged 70 plate and unflanged plate are welded together.

The accompanying drawings illustrate the preferred form of the invention, though it is to be understood that the invention is not limited to the exact details of construction shown and described, as it is obvious that various modifica-

tions thereof, within the scope of the claims, will occur to persons skilled in the art.

I claim:

1. In an open top railway car having spaced apart horizontal frame members, the combination of a pair of wall plates extending between and secured to said frame members to form a load retaining means therebetween, a portion of one of said plates overlapping a portion of the other plate, means securing said overlapping portions together, one of said wall plates having an integral flange at a vertical margin thereof closely adjacent the overlapping portions of said plates, each of said wall plates formed with an outwardly projecting panel to increase the cubical capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby parts of the adjacent panels and the flange cooperate to form a strut-beam between the frame members. 25

2. In an open top railway car having spaced apart horizontal frame members, the combination of a pair of wall plates extending between and secured to said frame members to form a load retaining means therebetween, a portion of one of said plates overlapping a portion of the other plate, means securing said overlapping portions together, one of said wall plates having an integral flange at a vertical margin thereof closely adjacent the overlapping portions of said plates, each of said wall plates formed with an outwardly projecting panel to increase the cubical capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby parts of the adjacent panels and the flange cooperate to form a strut-beam between the frame members, a part of the flange and the part of the flanged plate which overlaps the other plate being formed with spaced apart indentations to provide stiffening means for the flange. 45

3. In an open top railway car having spaced apart horizontal frame members, the combination of a pair of wall plates extending between and secured to said frame members to form a load retaining means therebetween, a portion of one of said plates overlapping a portion of the other plate, rivets forming means securing said overlapping portions together, one of said wall plates having an integral flange at a vertical margin thereof closely adjacent the overlapping portions of said plates, each of said wall plates formed with an outwardly projecting panel to increase the cubical capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby parts of the adjacent panels and the flange cooperate to form a strut-beam between the frame members, a part of the flange and the part of the flanged plate which overlaps the other plate being formed with spaced apart indentations to provide stiffening means for the flange. 55

- the part of the flanged plate which overlaps the other plate being formed with spaced apart indentations to provide stiffening means for the flange.
5. In an open top railway car having spaced apart horizontal frame members, the combination of a pair of wall plates extending between and secured to said frame members to form a load retaining means therebetween, a portion of one of said plates overlapping a portion of the other plate, means securing said overlapping portions together, one of said wall plates having an integral flange at a vertical margin thereof closely adjacent the overlapping portions of said plates, said flange provided with a reflare projecting toward the flanged plate, each of said wall plates formed with an outwardly projecting panel to increase the cubical capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby the flange, the reflare and the overlapping portion of the flanged wall plate form a channel shaped strut-beam between the frame members which is protected from the lading by the overlapping portion of said other plate.
5. In an open top railway car having spaced apart horizontal frame members, the combination of a pair of wall plates extending between and secured to said frame members to form a load retaining means therebetween, a portion of one of said plates overlapping a portion of the other plate, means securing said overlapping portions together, one of said wall plates having an integral flange at a vertical margin thereof closely adjacent the overlapping portions of said plates, said flange provided with a reflare projecting toward the flanged plate, each of said wall plates formed with an outwardly projecting panel to increase the cubical capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby the flange, the reflare and the overlapping portion of the flanged wall plate form a channel shaped strut-beam between the frame members which is protected from the lading by the overlapping portion of said other plate, and means to prevent said flange from deflecting laterally under stress comprising an element secured to said flange, said reflare and the portion of the flanged plate which overlaps the other of said plates.
8. In an open top railway car having spaced apart horizontal frame members, the combination of a pair of wall plates extending between and secured to said frame members to form a load retaining means therebetween, a portion of one of said plates overlapping a portion of the other plate, means securing said overlapping portions together, one of said wall plates having an integral flange at a vertical margin thereof closely adjacent the overlapping portions of said plates, each of said wall plates formed with an outwardly projecting panel to increase the cubical capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby parts of the adjacent panels and the flange cooperate to form a strut-beam between the frame members, and means to prevent said flange from deflecting laterally under stress comprising members secured to said flange and to said panels.
9. In an open top railway car having spaced apart horizontal frame members, the combination of a pair of wall plates extending between and secured to said frame members to form a load retaining means therebetween, a portion of one of said plates overlapping a portion of the other plate, means securing said overlapping portions together, one of said wall plates having an integral flange at a vertical margin thereof closely adjacent the overlapping portions of said plates, each of said wall plates formed with an outwardly projecting panel to increase the cubical capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby parts of the adjacent panels and the flange cooperate to form a strut-beam between the frame members, and means to prevent said flange from deflecting laterally under stress comprising members secured to said flange and to said panels.

cal capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby parts of the adjacent panels and the flange cooperate to form a strut-beam between the frame members, and means to prevent said flange from deflecting laterally under stress comprising members secured to said flange and to said panels, said members being positioned within the bounding plane of the outwardly projecting panels so as not to increase the width of the car.

10. In an open top railway car having spaced apart horizontal frame members, the combination of a pair of wall plates extending between and secured to said frame members to form a load retaining means therebetween, a portion of one of said plates overlapping a portion of the other plate, means securing said overlapping portions together, one of said wall plates having an integral flange at a vertical margin thereof closely adjacent the overlapping portions of the plates, said flange being secured to said frame members in the plane of said vertically extending flange, each of said wall plates formed with an outwardly projecting panel to increase the cubi-

cal capacity of the car, the panel of the flanged wall plate merging into the plate adjacent the edge of the other wall plate and the panel of the other wall plate merging into said other plate adjacent the base of the flange whereby the horizontal widths of the panels longitudinally of the car are increased and the cubical capacity of the car is increased and whereby parts of the adjacent panels and the flange cooperate to form a strut-beam between the frame members.

5

11. In an open top railway car having spaced apart frame members, the combination of a pair of wall plates extending between and secured to said frame members to form a load retaining means therebetween, one of said wall plates having an integral flange at a vertical margin thereof, each of said wall plates formed with an outwardly projecting panel to increase the cubical capacity of the car, the panel of the flanged wall plate merging into the plate adjacent the base of the flange and the panel of the other wall plate terminating in a sloping wall welded to said flanged plate adjacent the base of the flange whereby the horizontal widths of the panels longitudinally of the car are increased and the cubical capacity of the car is increased and whereby parts of the adjacent panels and the flange cooperate to form a strut-beam between the frame members.
